WRINGER

Noble H. Watts, Glendale, Calif., assignor to Lovell Manufacturing Company, Erie, Pa., a corporation of Pennsylvania

Application October 11, 1937, Serial No. 168,432

10 Claims. (Cl. 68—253)

This invention relates generally to power wringers and more particularly to pressure regulating and developing means for the rolls thereof.

All devices of this character made according to the prior art, and with which I am familiar, have provided some sort of spring means for developing pressure between the rolls of a wringer resulting in excessive stresses on the frame of the wringer thereby requiring a heavy frame, and considerable space. These springs would readily lose their elasticity and the forces which they exerted on the ends of the rolls were uneven in many cases, thereby making the wringing operation less efficient. The regulation of the pressure exerted by these springs was also very difficult because of the size of the springs and other structural impediments.

It is, accordingly, an object of my invention to overcome the above-mentioned defects in wringers and more particularly to provide a wringer in which the pressure between the rolls is controlled from the shaft of one of the rolls.

Another object of my invention is to provide a wringer which is efficient in operation, easy to construct, economical in cost, and which requires a minimum of space.

Another object of my invention is to provide a wringer wherein the power obtained through a friction slip clutch develops the pressure between the rolls.

Another object of my invention is to provide a wringer which has novel control means for the operation thereof.

Another object of my invention is to provide a wringer wherein all stresses are confined to the clutch and linkage system with only the torsional stresses on the frame.

Another object of my invention is to provide a wringer wherein the bottom roll power shaft is in one piece permitting alignment of the wringer on the shaft instead of forcing the shaft to align with the frame.

Another object of my invention is to provide a wringer wherein the pressure rolls may be separated by spring members when the wringer is at neutral position and without fabric between the rolls.

Another object of my invention is to provide a wringer wherein snubbing means are provided for preventing sudden separation of the rolls.

Other objects of my invention will become evident from the following detailed description, taken in conjunction with the accompanying drawings, in which

Fig. 1 is a side elevational view of my novel wringer.

Fig. 2 is a side elevational view partly in section and with the housing removed showing my novel clutch means for developing pressure between the rolls. 5

Fig. 3 is a fragmentary view showing the method of linkage from the lower or power shaft to the upper shaft, the upper and lower shafts carrying the pressure rolls. 10

Fig. 4 is a side elevational view of the flanged clutch housing shown in Fig. 2.

Fig. 5 is a side elevational view of the clutch disc which engages the splines in the clutch housing shown in Fig. 4. 15

Fig. 6 is a side elevational view of the clutch disc which engages the clutch disc shown in Fig. 5 and which moves with the power shaft shown in Fig. 2.

Fig. 7 is a side elevational view of the spring member used in the clutch mechanism. 20

Fig. 8 is a sectional view taken on a vertical plane through the center of the spring member of Fig. 7.

Fig. 9 is an end elevational view partly in section showing particular control members used in my novel wringer. 25

Fig. 10 is an end elevational view of a modified form of linkage between the upper and lower rolls wherein spring members are used to separate the rolls. 30

Fig. 11 is an end elevational view of a modified form of linkage between the upper and lower pressure roll.

Fig. 12 is an end elevational view of another modified form of linkage between the upper and lower rolls. 35

Referring to the drawings, the wringer shown generally in Fig. 2 comprises an outer housing having disposed therein end members 2 and 3. 40 The end members 2 and 3 carry suitable bearings 4 to journal the shafts 5 and 6 upon which are mounted the coacting pressure rolls 7 and 8. The lower roll 8 is preferably utilized as the power roll and the ends of the shaft 6 are splined at 45 9 and 10, the splines at 10 engaging with a driving member 11 which is adapted to drive the rolls 7 and 8 in a forward or reverse direction.

The driving means for the rolls 7 and 8 comprise a shaft 12 disposed in a post 13 and which has mounted on the upper end thereof a bevelled gear 14 in engagement with oppositely disposed bevelled gears 15 and 16 journaled in a revolvable frame 17 supported by a shoulder on the post 13. The control means for the operation of the 50 55

rolls 7 and 8 comprise a bar 18 disposed in the upper portion of the housing 1 having gears 19 mounted on each end thereof to engage rack members 21 and 22 which move tangentially of 5 the gears 19, and rotate the gear 23 through the rack member 24 disposed in a vertical plane with reference to the rack members 21, the rack member 24 moving with the rack members 21 and rotating the gear 23 in any desired direction. The 10 gear 23 is mounted on a shaft 25 journaled in the upper portion of the frame 17 and has an eccentrically disposed member 26 disposed on the bottom portion thereof which engages a peripheral groove 27 in the driving member 11 engaging 15 the driving shaft 6. Upon rotation of the gear 23 by means of the rotation of the bar 18 in any direction, the eccentric member 26 causes the teeth 28 on the driving member 11 to move into engagement with teeth 29 and 30 on the face of 20 the bevelled gears 15 and 16, thereby directly transmitting power from the bevelled gears 15 and 16 to the shaft 6 in accordance with the direction of rotation of the bevelled gear 15 or 16 in which the driving member 11 is in engagement. The frame 17 supports the housing 1 and rotates about the wringer post 13. A conventional lever 31 is provided to set the wringer in any position desired.

Coming now to the gist of this invention, which 30 is broadly the development of pressure between the top roll and the bottom roll through the medium of the bottom roll shaft 6, the splines 32 on clutch discs 33 (Fig. 6), engage with the splines 9 and 10 on both ends of the shaft 6 and are rotatable therewith and movable longitudinally thereof. The discs 33 are adapted to frictionally engage the clutch discs 34 which are freely mounted on the shaft 6 and spring members 35 are provided to urge the discs 33 and 34 35 into frictional engagement. Flanged clutch housings 36 are freely mounted on the shaft 6 and are splined to and rotatable with the clutch discs 34, the internal periphery of the flanged housings 36 being provided with splines 37 which 40 engage the outer projecting portions 38 of the clutch discs 34 thereby permitting relative longitudinal movement of the discs 34 but causing the housings 36 to rotate with the discs 34. The housings 36 with the complete clutch unit move 45 freely on the shaft 6 without end thrust. A spring member 35 urges the group of discs 34 against the driving disc 33. Flanges 39 are disposed adjacent the housings 36 and anchor pins 40 are mounted near the outer periphery thereof. Other anchor pins 41 are mounted on the 50 end walls 2 and 3 and are stationary. Pull tapes or belts 42, preferably forming endless loops as pull cables shown in Fig. 3, are looped around the bearings 4 and anchor pins 40. The rotation 55 of the lower or power shaft 6 causes the rotation of the discs 33 splined thereto. The discs 33 upon rotation in frictional engagement with the discs 34 splined to the clutch housings 36 urge the discs 34 with housing 36 to rotate, the force 60 of the springs 35 bearing against the discs 34 defining the limits of the rotational force which will be exerted on the tapes 42 before a slippage takes place between the discs 33 and 34. The tapes 42 and anchor pins 40 and 41 are so constructed and placed that a block and tackle effect is formed between the lower and upper shafts 5 and 6, thereby multiplying the leverage rates therebetween. The housings 36 are urged to rotate by the discs 34 splined thereto and thereby 65 the anchor pins 40 movable therewith exerts -

tensional pull on the tapes 42 which causes the upper roll shaft 5 to be forced downwardly an amount proportional to the torsional effect exerted by the clutch which in turn is dependent on the force exerted by the spring members 35. It will be apparent that the upper anchor pins 41 are not absolutely necessary in that the tapes 42 could be anchored on a bearing on the lower shaft 6. When the rolls 7 and 8 are separated, the pull tape unwinds to provide a snubbing action between the rolls 7 and 8. 10

In operation, the wringer is placed in its desired position for operation and the lever 31 locks it in this position. The shaft 6 and gears 15 and 16 are rotated by the driving mechanism not shown and the teeth 29 on the driving member 11 splined on the power shaft 6 is forced into engagement with the teeth 29 or 30 of the forward or reverse gears 15 or 16 by rotation of the control bar 18. The rotation of the shaft 6 15 causes rotation of the discs 33 splined thereon which in turn cause rotation of the discs 34 splined to the housing 36 through frictional engagement therewith, the force of the spring members 35 defining the limits of the rotational force 20 exerted. The anchor pins 40 rotatable with the housing 36 exert a winding effect and a tensional force on the tapes 42 which thereby causes a downward force on the upper roll shaft 5. It 25 will be apparent that pressure force of the spring members 35 used determines the force which is exerted downwardly by the belt 42 since the greater the force of the spring members 35, the greater will be the friction between the discs 33 and 34. The only force exerted on the frame 30 of the wringer is a slight torsional strain; otherwise, all of the strain is taken by the shaft 6 of the lower roll 8. The lower roll 8 is utilized as the power roll in my preferred form but it will be evident that any roll may be utilized for this 35 purpose without departing from the spirit of this invention. The unwinding of the pull tapes 42 upon separation of the rolls 7 and 8 provides an approximately uniform pressure and also a snubbing action. 40

Fig. 9 shows a means for automatically reversing the tilt of the tilting drain board 50 when the rolls 7 and 8 are operated in a forward or reverse direction, this means comprising a crank arm 51 rotatably secured to the control bar 18 and attached to a link 52 with a projecting pin 53 on the lower portion thereof for engaging the underside of the drain board 50. When the control bar 18 is rotated to cause the rolls 7 and 8 to move in forward or reverse direction, the crank arm 51 will rotate with the control bar 18 and tilt the drain board 50 in the proper position in relation to the direction of rotation of the rolls 7 and 8. 45

Fig. 10 is an end view which shows substantially the same construction as that shown in Fig. 3 with the exception that spring members 60 are disposed on each end of the shafts 61 and 62 to effect a full separation thereof when the wringer is in a neutral position. 50

Fig. 11 is a modified form of linkage between the upper and lower roll shafts 70 and 71, only one end of the wringer being shown in Fig. 11. In this arrangement, the lower anchor pin 72 is disposed in the same position as in the other constructions but the looped tape 73 is disposed directly around bearing 4 of the upper shaft 70 to effect a direct downward pull on the upper shaft 70. 55

Fig. 12 is another modified form of linkage be- 70

tween the upper and lower roll shafts 80 and 81 with one end of the wringer shown. In this construction a cam member 82 is disposed on the lower shaft 81 and rotates therewith. Projecting portions 83 on the cam member 82 engage the external surface of the tape 84 and the projecting portions 83 of the cam member 82 are placed in such a position with relation to the anchor pin 85 that upon rotation of the cam member 82 in a clockwise direction when in a position as shown in Fig. 12, a lesser downward force on the upper roll shaft will be exerted by the tape 84.

It will be apparent that I have provided a wringer which requires a minimum amount of space, which is simple in construction and cheap in cost, which has a new, original, and efficient means for developing pressure between the co-acting rolls, which has novel control means, which is safe, and which has many other advantages in construction and in means of control.

Various changes may be made in the specific embodiment of the present invention without departing from the spirit thereof, or within the scope of the appended claims.

What I claim is:

1. In a wringer, a power roll, a second roll coaxing therewith, shafts upon which said rolls are mounted, tension means for linking said shafts together, and a clutch mounted on said power roll and in engagement therewith for exerting a predetermined pressure on said rolls through said tension means, said clutch comprising driving and driven disc members in frictional engagement, the driving disc members being rotated by said power shaft and a spring member urging said discs into frictional engagement whereby the pressure between said rolls is regulated.

2. In a wringer, a power rotated roll, a coaxing pressure roll, tension means linking said rolls, and a friction clutch having one part rotated by one of said rolls and a second part thereof frictionally actuated by said first mentioned part and operatively connected to said tension means to create a pressure between said rolls.

3. In a wringer, a power rotated roll, a coaxing pressure roll, shafts for said rolls, tension means for linking said shafts together comprising a band, and a friction means having one part rotated by one of said shafts and a second part thereof frictionally actuated by said first mentioned part operatively engaged with said band to tension said band and draw said rolls together.

4. In a wringer, a power rotated roll, a coaxing pressure roll, shafts for said rolls, tension

means linking said shafts, friction means having one part rotated by one of said shafts and a second part thereof frictionally actuated by said first mentioned part and operatively connected to said tension means for creating a pressure between said rolls, and means for predetermining the amount of pressure between said rolls.

5. In a wringer, a power rotated roll, a second roll, shafts for said rolls, tension means for linking said shafts together comprising a looped band, an anchor member to which said band is engaged, and means operatively connected to said power rotated shaft and to said anchor member to create a pressure between said rolls.

6. In a wringer, a power rotated roll, a second roll, shafts for said rolls, tension means for linking said shafts together comprising a band and anchor members therefor connecting said shafts so positioned that the ratio of force transfer through the band is multiplied, and means operatively connected to said power rotated roll and to said anchor member to create a pressure between said rolls.

7. In a wringer, a power rotated roll, a second roll, tension means for linking said rolls together comprising a band, anchor points for said band and a cam member engaging said band for decreasing the pressure exerted on said rolls beyond a predetermined degree of separation thereof, and means operatively engaged with said power rotated roll and one of said anchor points for creating a pressure between said rolls.

8. In a wringer, a power shaft, means for driving said shaft in a forward or reverse direction mounted on said shaft, power means for operating said driving means, a second shaft, rolls carried by said shafts, tension means for linking said shafts, and means operatively engaged with said power shaft and said tension means for creating pressure between said rolls.

9. In a wringer, a power rotated roll, a coaxing pressure roll, tension means linking said rolls, and friction means having one part rotated by one of said rolls and a second part thereof frictionally actuated by said first mentioned part and operatively connected with said tension means whereby the pressure exerted between said rolls is substantially uniform at any lateral position thereof.

10. In a wringer, a power rotated roll, a second roll, and means for maintaining a substantially uniform pressure at any point of separation of said rolls comprising tension means for linking said rolls together and friction means operatively engaged with said power roll and said tension means.

NOBLE H. WATTS.
